(57) **CLAIM**

The ornamental design for a cooler, as shown and described.

DESCRIPTION

In a preferred embodiment, the nature of this product is a front or front portion for a pull-out drawer or rack refrigerated unit used for the cool storage of food and/or beverages.

FIG. 1 is a right, top, front perspective view of a cooler according to our new design;

FIG. 2 is a front elevational view thereof;

FIG. 3 is a right side elevational view thereof, the left side elevational view being a mirror image thereof;

FIG. 4 is a top plan view thereof; and,

FIG. 5 is a bottom plan view thereof.

The broken lines shown in the drawing disclosure are for illustrative purposes only and form no part of the claimed design.

1 Claim, 5 Drawing Sheets

FIG. 2

FIG. 3

FIG. 4

FIG. 5
